LIPSTICK APPLICATOR

James J. Arnold, West Milwaukee, Wis.

Application September 20, 1946, Serial No. 698,231

3 Claims. (Cl. 15—227)

1

This invention relates to an applicator for lipstick and the like.

It is an object of the invention to provide an improved and simple and inexpensive applicator which is readily cleaned but so cheap that it may be treated as disposable; which may readily be carried and compactly stored on a lipstick case or holder without possibility of soiling the clothes or purse of the user, and which is instantly available for use and readily applicable to and detachable from the mounting device upon which it is preferably carried.

In the drawings:

Fig. 1 is a view in perspective showing the improved device as it appears when mounted for carrying.

Fig. 2 is a view showing the mount in side elevation and the applicator in transverse section.

Fig. 3 is an enlarged detailed view showing a preferred type of connection between the applicator and its carrier ring.

Fig. 4 is a view in perspective showing the applicator separately.

Fig. 5 is a side elevation of the applicator illustrating it on a somewhat reduced scale as it is mounted for use.

Fig. 6 is a detail view similar to Fig. 3 showing the applicator in its reverse position respecting the ring.

The tube or case 6 may be a generally conventional lipstick case with which I am here concerned only insofar as it is adapted for use as a support for my improved applicator. For this purpose the case 6 of Fig. 1 is preferably provided with embossed ribs 7, while the case 60 of Fig. 2 is provided with a circular boss at 8.

The applicator comprises a piece of soft and flexible material having the general form of a thimble or finger cot, as indicated at 10. I desire that the flexibility be such that the applicator may with facility be turned inside out to expose a fresh and clean surface. I have found chamois skin ideal for the purpose.

The lower margin of the skin or other material is anchored in a ring 11. While the skin may be adhesively or otherwise connected to the ring, I prefer to make the ring in two parts as shown in Fig. 3, the inner part 12 comprising a small annulus over which the skin is expanded, and the outer part 14 being L-shaped in cross section and comprising a flange 13.

The thimble-like applicator is preferably made to fit exactly on the exterior of the lipstick case 6 as shown in Figs. 1 and 2. When so positioned, the exposed surface 10a will be kept free of cos-

metics and the surface 10b used to apply the lipstick or other cosmetic will be innermost and thereby protected from contact with the user's clothing or purse. The ring 11 engages frictionally over the ribs 7 or the boss 8 to hold the applicator releasably in position. When it is desired to use the applicator, the applicator is withdrawn from the case 6 and turned inside out from the dotted line position of Fig. 4 to the full line position thereof. This may conveniently be done by applying one of the operator's fingers to the end of the mounted applicator and then pulling the ring 11 from the position shown in Figs. 1 and 2 upwardly along the case and over the finger to the ultimate position shown in Fig. 5. The device is then used to apply or distribute cosmetics and, by placing the tip of the covered finger in contact with the end of the case, the ring 11 may be drawn from the finger onto the case, again turning the applicator 10 inside out and restoring its used surface 10b to a protected interior position against the end wall of the case or mounting member 6 or 60.

As indicated above, the applicator may be used for cosmetics other than lipstick, and it is not necessary that the cosmetics be stored in the shell or case 6 or 60, nor is it required that the improved applicator necessarily be carried on such a case or shell. When the applicator is inside out, its used surface will be concealed and protected whether or not the applicator is so mounted.

I claim:

1. A device of the character described comprising the combination with a mount having substantially the perimeter of a finger tip, and a flexible hollow finger cot approximately the length of the finger from its tip to the adjacent joint and stretched about the end of said mount and conformed thereby to the end thereof and provided with marginal re-enforcement encircling said mount, said cot having an applicator surface innermost and engaged with said mount and being freely reversible upon removal from said mount to expose said surface for use.

2. The device set forth in claim 1 in which said mount has means with which said marginal reinforcement is engaged for the retention of said cot on said mount.

3. An applicator for cosmetics comprising a flexible finger cot of no greater length than the user's finger from the tip to the adjacent joint, and a finger ring with which marginal portions of said cot are permanently connected, the said cot having an applicator surface normally in-

3

teriorly disposed and being freely reversible through said ring to an inside-out position in which said applicator surface is exposed, said ring comprising separably inner and outer annular elements, the outer of said elements being 5 shouldered and the said elements being in frictional clamping engagement upon the said margins of said cot.
